UNITED STATES PATENT OFFICE.

HUGH GORDON ROSS, OF OTTAWA, ONTARIO, CANADA.

ELECTRIC CONNECTOR.

Application filed December 6, 1920. Serial No. 428,500.

To all whom it may concern:

Be it known that I, HUGH GORDON Ross, a subject of the King of Great Britain, and resident of the city of Ottawa, in the Province of Ontario, Dominion of Canada, have invented certain new and useful Improvements in Electric Connectors, of which the following is a specification.

This invention relates to improvements in electric connectors particularly of the type used to connect conductors to electric irons, stoves, heaters and the like; and the objects of the invention are to provide means for automatically disconnecting the current when the heat of the utensil exceeds a predetermined amount; further objects are to render the device of a simple and compact construction, composed of few parts all well designed to perform the functions required of them; and it consists essentially of the improved construction hereinafter described in detail in the accompanying specification and drawings.

In the drawings:

Figure 1 is a plan view of a connector embodying the present invention with the top part removed and showing it connected at the terminals of an iron or the like.

Figure 2 is a sectional view on the line x—x, Figure 1.

Figure 3 is a sectional view on the line y—y, Figure 1.

In the drawings like characters of reference indicate corresponding parts in all the figures.

Referring to the drawings:

A and B represent two parts constituting the casing of the connector formed of suitable insulating material such as vulcanite or fibre. 10 and 11 indicate tubular connecting members adapted to connect with the connecting posts or pins 12 and 13 on an electrically heated utensil C which may, for instance, be an iron.

In accordance with the present invention, the connector has within the same a thermostatic control support, and break means are also contained in the support. These means including a metallic thermostatic couple 14 which may be composed of two thin strips of metal having different coefficients of expansion which are secured to a flat spring 15 mounted within a recess 16, the flat spring 15 at one end being connected to a metallic con-

ducting pin 17 designed to project outwardly 55 from the connector and abut, bear against, or enter a suitable recess in the utensil C.

The opposite end of the spring 15 to that connected to the conducting pin 17 is free and designed to engage with the end of a 60 threaded conducting pin 18 mounted in the end of the conductor 11 and adapted to be adjusted by means of a mill head 19 on the outer end thereof, the pin 18 extending in a suitable recess 20 formed in the connector. 65 To prevent excess movement of the pin in opposite directions, collars 21 and 22 are formed thereon.

23 indicates one of the conductors for supplying current to the connector which is 70 connected to the member 10. The other conductor 24 is connected to a binding post 25 which is connected by a conductor 26 with the conducting post 17. The conductors 23 and 24 and the connector may be surrounded by a reinforcing spring 27 in accordance 75 with the usual practice.

It will be seen that should the temperature of the iron, or other utensil, C reach an excessive amount, the thermostatic couple 14 will move the spring 15 away from the end of the conductor 18 to the post indicated in dotted lines in Figure 1 thus breaking the connection and preventing overheating.

As many changes could be made in the above construction, and many apparently widely different embodiments of my invention within the scope of the claims, constructed without departing from the spirit 90 or scope thereof, it is intended that all matter contained in the accompanying specification and drawings shall be interpreted as illustrative and not in a limiting sense.

What I claim as my invention is:

1. An electric connector comprising a two-part connector of insulating material, a pair of tubular sockets mounted within the same, a thermostatic couple, a spring connected to the couple, a contact member connected to one of the sockets and adapted to be engaged by the spring.

2. An electric connector comprising a two-part connector of insulating material, a pair of tubular sockets mounted within the same, 105 a thermostatic couple, a spring connected to the couple, a contact member connected to one of the sockets and adapted to be en-

gaged by the spring, and a heat conducting member connected to the spring and extending exterior to the connector.

3. An electric connector comprising an insulating member, a current connecting means on the insulating member, a heat conducting member projecting outwardly from the insulating member, a thermostatic couple mounted on the insulating member, including a spring member and a conducting

pin also on the insulating member adapted to co-operate with the spring to break the electric connections when the temperature reaches an excessive amount.

In witness whereof I have hereunto set 15 my hand in the presence of a witness.

HUGH GORDON ROSS.

Witness:

RUSSEL S. SMART.
